UNITED STATES PATENT OFFICE.

JOHN M. VAN HEUSEN, OF BOSTON, MASSACHUSETTS, ASSIGNOR TO INNOVATION SHIRT COMPANY, OF NEW YORK, N. Y., A CORPORATION OF NEW YORK.

COMBINATION-GARMENT.

1,186,866.

Specification of Letters Patent. Patented June 13, 1916.

Application filed October 22, 1912. Serial No. 727,102.

To all whom it may concern:

Be it known that I, JOHN M. VAN HEUSEN, a citizen of the United States, residing at Boston, county of Suffolk, State of Massachusetts, have invented certain new and useful Improvements in Combination-Garments; and I do hereby declare the following to be a full, clear, and exact description of the invention, such as will enable others skilled in the art to which it appertains to make and use the same.

My invention relates to certain new and useful improvements in combination garments, and particularly combination garments intended to be put on and taken off in the same manner as a coat-shirt, and which shall nevertheless embody, in a single structure, an upper body portion, and a lower thigh drawers portion which terminates above the knee.

The characteristic feature of my invention is that, while embodying in its structure facility for putting it on and taking it off after the manner of a coat-shirt, it is nevertheless, entirely closed in the rear and along the crotch seams, to a point well up on the front side of the garment, sufficient fullness being provided in the seat portion to permit the garment to be worn with comfort. As thus constructed, the garment is devoid of the usual overlapping rear flaps customary in combination garments, is of substantially a single thickness throughout, and is reliably but releasably closed by the front buttons and button hole edge. The resulting economy in material and cost of manufacture is therefore accompanied with simplicity of construction and adaptability to individual fit, while, at the same time, the garment is especially comfortable to the wearer, and can even be worn as an outer garment, as, for instance, for track-racing and as pajamas.

In the accompanying drawing, Figure 1 represents a front view of the garment in its preferred form; Fig. 2 represents a rear view thereof, with the main portion of the sleeves shown in Fig. 1 omitted; Fig. 3 represents a front view of the garment unbuttoned; and Fig. 4 represents a rear view thereof with the wearer in a seated posture.

Similar letters of reference indicate similar parts throughout the several views.

Referring to the drawing, A indicates the main body portion of the garment, and B

indicates the thigh portions thereof. The main body portion C of the back of the garment is connected with the seat portion D thereof in such manner as to provide the necessary fullness to permit the wearer to either bend over or to seat himself without discomfort, the parts being appropriately patterned, gathered and assembled, as will be understood by those skilled in the art. The rear or seat portion of the garment is entirely and permanently closed, as indicated, from the waist-line downwardly and this closure is preserved along the two crotch seams b to a point c well up on the front portion of the garment. The garment is thus entirely closed in the rear, and can be therefore appropriately fitted to the wearer.

In front, the garment is provided with a set of buttons or like releasable fastenings d extending down the edge of one of the front panels and being then diverted laterally along the top side of the opposite drawer-leg; that is to say, beyond the line of the crotch seam of the opposite drawer-leg and at such a distance therefrom as may be desired. As shown, however, this lateral divergence of the buttons or fastenings need not be more than is indicated in the drawing, the main consideration being that the fastenings shall be readily accessible to the wearer. For purposes of illustration, the garment is shown in the drawing as distended at its leg portions, as it would be while being worn. With the leg portions collapsed, however, as will be understood, the free edge of the button-hole carrying panel may be, and usually will be made straight, as indicated in Figs. 1 and 3 so that, with striped goods, for instance, the effect of the pattern will be preserved. Whether the line of joining of the buttons and button holes is along the top one of the legs or the other is a matter of choice, and is immaterial to the general function of the garment. In general, however, it is preferred to effect the fastening along the top of the left leg, as shown.

By unbuttoning the garment from below upward for a sufficient distance it is entirely feasible, when desired, without taking off the garment, and before sitting down, to fully throw back the leg portion of the button hole panel and to shift it and the seat portion entirely out of the way, thus wholly dispensing with the necessity for

open or separable rear flaps, while fully preserving their intended function. This feature of convenience of the garment is particularly illustrated in Fig. 4.

5 Having thus described my invention, what I claim is:

1. A combination garment, consisting of a shirt and knee drawers, said garment being provided with releasable fastening devices extending down the front thereof and continuing laterally of the crotch, so as to permit it to be conveniently put on and taken off, and being further provided with a permanently closed seat; substantially as 10 described.

15 2. A combination garment, consisting of

a shirt and knee drawers, said garment being provided with releasable fastening devices extending down the front thereof and continuing laterally of the crotch, so as to 20 permit it to be conveniently put on and taken off, and being further provided with a permanently closed seat of substantially a single thickness of fabric; substantially as described.

25 In testimony whereof I affix my signature, in presence of two witnesses.

JOHN M. VAN HEUSEN.
